D. E. Somes,

Air Cooler.

No. 101,392.

Patented Mar. 29, 1870.

Attest
J. D. G. G. S.
D. Somes.

Inventor
D. Somes.

UNITED STATES PATENT OFFICE.

DANIEL E. SOMES, OF WASHINGTON, DISTRICT OF COLUMBIA.

IMPROVEMENT IN COOLING AIR AND LIQUIDS.

Specification forming part of Letters Patent No. **101,392**, dated March 29, 1870.

To all whom it may concern:

Be it known that I, DANIEL E. SOMES, of Washington, in the county of Washington, and in the District of Columbia, have invented a new and useful Improved Apparatus and Process of Cooling Air, Liquids, and other Substances; and I do hereby declare that the following is a full, clear, and exact description thereof, reference being had to the annexed drawings, making part of this specification, in which—

Figure 1 is a section of a building or apartment with my improved devices arranged therein. Fig. 2 is a horizontal section on line *xx* of Fig. 1. Fig. 3 is a transverse section of a building, showing a roof covered upon the outside with fibrous material, which is kept moist by water delivered upon it. Fig. 4 shows a cooling-tube arranged over a tank for cooling beer.

The same letters are used in all the figures to designate identical parts.

My invention relates to apparatus for cooling air and drying the same, especially designed for use in meat-packing houses, preserving-houses, breweries, vessels, cars, &c., which it is desirable to cool or ventilate; and my improvements consist in the construction, combination, and arrangement of devices for producing the above-indicated results, as will more fully appear from the following specification and claims.

To enable those skilled in the art to make and use my invention, I will proceed to describe its construction and operation.

In the annexed drawings, A represents a wall, inclosing a chamber which may be used as a meat-packing room, preserving-room, cooling-room of a brewery, &c. This wall I construct, by preference, as shown, with spaces between the layers, which may be simply air-spaces, or they may be packed with good non-conducting substances. The room is covered by a roof, A¹, also built multiple, as shown.

In some cases I prefer to construct this roof of metal plates, to be covered upon the outside with fibrous material, cloth, tow, or the like, which is constantly moistened by sprays of water discharged upon it from a pipe, A², for the purpose of evaporating the water thereon, whereby heat is abstracted from the air under the roof in the room, cooling it and

causing it to fall, while warmer air takes its place, to be cooled in its turn. This roof may be built of double walls, as shown in Fig. 3, with an intervening air-space. In this case suitable valves are arranged in the inner wall of such roof, which can be operated from the floor by means of chains or cords.

B represents a hollow cylinder or tube, extending from the bottom of the tank D upward through the roof to some distance above the same. Near its upper end a partition or diaphragm, B¹, is placed across it, forming a water-tight joint with the same, so as to form a water-reservoir on top of such tube, into which water is delivered through a pipe, B², from any convenient source.

The shell of the water-reservoir is perforated, as shown. The water passing through such perforations falls upon a covering, B³, of fibrous material wound around the tube all the way down the same to the point where it is enlarged to form a chamber for the reception of ice or other cooling substances. This enlarged portion is marked B⁴ in Fig. 1, it being provided with a suitable door, through which to introduce the cooling substance. By the constant evaporation of water around the tube the air in it will be reduced in temperature. Near the roof, and in the room, the tube has valves B⁵, which, when opened, will cause the warm air in the upper part of the room to enter such tube, where it is then cooled.

When this tube is arranged in the upper story of a building, I place a series of vertical pipes, B⁶, in its lower part, extending through the floor, so that the room below may be cooled from above by the cool air passing down through them, such pipes being provided with suitable valves to open or shut them.

C represents a horizontal flue, passing around the tube B a little distance above its ice-chamber, and connected at one end to a suction-blower, C¹, which draws the air through it for the purpose of rapidly evaporating the water on and in the fibrous covering, and discharges it upon a series of water-pipes, C², inclosed in a chamber, C³, to again abstract from it the watery vapor with which it has been charged on passing over the wet tube B.

The dried air passes out of the chamber C³ back into the room, to be used over again, while the watery vapor is condensed on the

water-pipes and falls into the bottom of the chamber, from which it may be drawn off from time to time.

Instead of the water-pipes, plates of metal or other good condensing substance may be used for drying the air.

D represents what may be a tank for salting meat, placed upon the floor of the room surrounding the ice-chamber of the tube B; or it may be a box containing a number of preserving-chambers, in which to preserve fruits, vegetables, &c.

E represents a tube, which is employed for cooling the air in the room without the assistance of cooling substances, it being either tapering, as shown, or straight, as may be preferred. Its top is some distance above the roof, and carries a water-reservoir like the tube B, into which water is delivered, to be again discharged upon a fibrous covering, E¹, wound around the tube, for the purpose of evaporation to cool the air in the pipe. The lower end of this pipe or tube is left open, a pan, E², being suspended under it to catch the water which results from the watery vapor in the air of the room being condensed on the cold surface of the pipe. Instead of this pan, gutters may be used, formed around the lower edge of the tube, as shown. In it an inner tube, E³, is arranged, with an air-space between the two, such inner tube extending up in the outer one for a considerable distance, the object being to provide a flue for the warmer air in the room to pass up. This warm air, passing over the top of the inner flue or tube, comes in contact with the cold surface of the outer one and is cooled, on which it falls down the space between the two tubes back into the room.

Valves E⁴ may also be arranged in the outer tube, near the roof, to admit the warm air into it to be cooled, if desired.

F represents a cylindrical shell, resting upon legs or standards, and inclosing a series of water-pipes, F¹, it being open at both ends.

Cold water drawn from a well, F², is made to circulate through these pipes, from which, after passing through the whole series, it is again discharged into the same well. The surfaces of these pipes will thus be kept cold, and the air, on coming in contact with them, will be cooled, and its watery vapor be condensed on the pipes, thus drying it, in which cooled and dried condition it falls down upon the articles which may be placed in a tank, D, under the pipes or back into the room. The condensed vapor is caught by the tank or by a pan, from which it can be drawn off.

G and G¹ are ventilating-tubes, provided with the ordinary hood and vane on top and dampers or valves beneath, the hoods and vanes being so arranged, respectively, that the wind will blow into one, to be directed into the room, while the air is drawn by the other tube out of the room and discharged into the atmosphere. The tube G, through which the wind blows into the room, is also provided

with the appliances for evaporation, like the tubes B and E.

In Fig. 4 I have shown a tank used for cooling beer, arranged under a cooling-tube such as described. I propose to cover the tank, so that the cold air passing down the tube shall come in contact with the beer only, which enables me to reduce its temperature in a much shorter time than is accomplished in the ordinary manner.

In Fig. 3 I have shown the roof of the building or apartment supported by pillars. Whenever such pillars are employed, I propose to let water circulate through them, for the purpose of cooling the air in the room, as also of drying the same. Its watery vapor, with which it may be charged, on coming in contact with the cold surface of the pillars, condensing, will run down them, and may be drawn off by means of gutters, or in other convenient manner. To this end I cast nozzles on the base of each pillar and near the capital, to which to connect the water-pipes, as shown in said figure. In such cases the ends of the pillars must, of course, be closed. Hereby a simple, cheap, and very effective means is obtained to produce the results sought to be effected.

Having thus described my invention, what I claim, and desire to secure by Letters Patent, is—

1. A roof covered with fibrous material, and cooled substantially in the manner set forth.
2. In combination with a roof covered with fibrous material, and cooled as set forth, an inner roof or ceiling with an intervening air-space and dampers, substantially as set forth.
3. The tube B, with a fibrous jacket and means for moistening the same, in combination with the flue C and blower C¹, substantially as set forth.
4. The condensing chamber or apparatus, the flue C, and the blower C¹, substantially as and for the purpose set forth.
5. The tube B, flue C, blower C¹, and condensing chamber or apparatus, substantially as set forth.
6. The cooling-tube E, with valves E⁴ and inner tube, E³, substantially as set forth.
7. A building or apartment with the cooling-tubes B or E and ventilating-tubes G and G¹, substantially as set forth.
8. The water-pipes F¹, inclosing shell or casting F, with a tank or chamber below such shell, substantially as set forth.
9. A building or apartment with pillars, through which water is made to circulate, substantially as set forth.
10. Any one or more of the herein-described devices or processes for cooling or drying, in combination with a building or apartment constructed with double or multiple walls, substantially as set forth.
